B. D. BOHANAN.
MACHINE FOR REMOVING SURPLUS MATERIAL.
APPLICATION FILED JULY 24, 1916.

Patented Aug. 31, 1920.

UNITED STATES PATENT OFFICE.

BUDD D. BOHANAN, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR REMOVING SURPLUS MATERIAL.

1,351,153.

Specification of Letters Patent. Patented Aug. 31, 1920.

Application filed July 24, 1916. Serial No. 110,942.

To all whom it may concern:

Be it known that I, BUDD D. BOHANAN, a citizen of the United States, residing at Boston, in the county of Suffolk and State of Massachusetts, have invented certain Improvements in Machines for Removing Surplus Material, of which the following description, in connection with the accompanying drawings, is a specification, like reference characters on the drawings indicating like parts in the several figures.

This invention relates to cutting machines for use in the manufacture of boots and shoes and is herein illustrated in connection with a machine for removing surplus material projecting beyond the seam which joins the quarters to the vamp of a shoe.

In the manufacture of shoes, there are several thicknesses of material at the point where the lower forward portions of the quarters are attached to the throat of the vamp. For example in a lace balmoral boot, there may be in addition to the quarters and the vamp, the linings of the quarters, the lacing strips, the lacing strip stays and certain other pieces of reinforcing material. The stitches which attach the quarters to the vamp pass through all of these articles so that a considerable amount of surplus material projects beyond the seam. This material, if allowed to remain, forms an objectionable bunch which makes the shoe more or less unsightly and uncomfortable.

Hitherto this operation has been carried out by hand, and the general object of the present invention is to provide a machine for performing the operation.

One feature of the present invention comprises a machine for removing such surplus material having a knife, a support for the surplus material, and means for operating the knife and for causing relative movement between the knife and support to sever said material.

It is desirable to cut off the surplus material as close as practicable to the seam but to avoid cutting the stitches. To this end another feature of the invention comprises in a machine of the class described a support having a narrow end adapted to extend close

to the seam and a supporting face inclined to the direction of cut of the knife, and means for presenting the work to the knife while maintaining the seam out of the path of the cut of the knife. By properly locating the support and the knife, it is thus possible to cut close to the seam without in any case cutting into it.

These and other features of the invention, including certain details of construction and combinations of parts will be described in connection with an illustrative machine and pointed out in the appended claims.

Referring now to the accompanying drawings.

Figure 1 is a perspective of a portion of a machine in which the present invention is embodied;

Fig. 2 is a detail in perspective showing the surplus material placed upon the support in position to be presented to the knife;

Fig. 3 is a detail in section on the line 3—3 of Fig. 1 showing the mechanism for moving the support, the support being in position to receive the work;

Fig. 4 is a similar section showing the work support in position to cause the knife to operate upon the work. In all the figures a guard which covers all of the knife except that portion opposite the work support has been omitted to promote clearness.

The illustrative machine comprises a band knife 5 running over drums of usual form, two of which are shown at 7, said drums being rotated by any suitable mechanism, not shown. Fastened to the frame 9 of the machine is a bracket 11, through which as well as through bars 13 and knife guides 15 pass screw bolts 17 by which these parts are fastened to the frame of the machine. Between the knife guides 15 the work support is located, said support having an inclined operative face with which the knife co-operates and a narrow forward end adapted to extend close to the seam as best shown in Fig. 95.

4. This work support is herein shown as composed of a hardened block 19 mounted on a carrier 21, said parts being fastened together by a screw 23. The carrier has a flat under face having an inclined forward end 100

25, the flat face normally resting upon the bottom of a guideway formed by the flat upper face of the bracket 11, and the inclined end being adapted to engage and ride 5 up an upwardly inclined face 27, formed on the bracket 11. The carrier 21 is held from sidewise movement by guides, one of which is shown at 29, said guides being fastened to the bracket 11 by screws 31. A leaf spring 10 33 bears upon the upper side of the work support, tending at all times to hold it down but permitting it to rise into the position shown in Fig. 4 when moved toward the knife. 15 The carrier 21 and work support 19 are normally held in the retracted position shown in Fig. 3 by a coiled spring 35 fastened at its upper end to the bracket 11 and at its lower end to the end of the horizontal 20 arm of a bell crank lever 37, said lever being pivoted at 39 to a stationary lug 41 and having in its vertical arm a slot 43. Through this slot passes a pin 45 carried by a yoke 47 the stem of which passes through a slot 25 in the bracket 11, through a bore in the carrier 21 and receives a nut 51 on its upper end. A treadle rod 53 pivoted to the bell crank lever at 55 is connected to a treadle, not shown. From the foregoing it will be 30 evident that the work support is normally held in the position shown in Fig. 3 and that depression of the treadle will move it forwardly and upwardly into the position shown in Fig. 4 so as to present the work 35 to the knife.

As has been explained above, the purpose 40 of the present machine is to remove surplus material which projects beyond a seam, and this surplus material may consist of the ends or margins of various articles such as linings, stays, reinforcements, etc. In order to simplify the drawings and the explanation of the operation of the machine there has been shown an unlined upper comprising 45 two quarters 100 attached to a vamp 200, a single reinforcing piece 300 having been interposed between them and the three stitched together, the reinforcing piece in the present case being a small piece of leather 50 of circular outline located at the throat of the vamp at the point of junction of the lower forward ends of the quarters. It is at this point that an objectionable bunch of 55 surplus material accumulates in the manufacture of the upper of a shoe, and ordinarily this material consists of the ends or margins of several pieces of leather or cloth.

In the operation of the machine the upper 60 is turned wrong side out and presented to the support 19 while said support is in the position shown in Fig. 3 with the narrow forward end of said support extending close to the seam 50 and between the surplus material and the vamp, said surplus material 65 resting upon the inclined upper face of

the support. The treadle is then depressed, whereupon the support is moved toward the knife and upwardly into the position shown in Fig. 4, and the projecting ends of the quarters 100 and the projecting end of the 70 reinforcing piece 300 are severed by a draw cut on a bevel. Upon release of the treadle the support is returned to the position shown in Fig. 3.

Although the invention has been set forth 75 in connection with a particular machine, it should be understood that the invention is not limited in the scope of its application to the particular machine shown and described.

Having thus described my invention, I claim as new and desire to secure by Letters Patent of the United States:

1. A machine for removing surplus material projecting beyond a seam which joins 85 two or more flexible articles, having in combination, a knife, means for operating the knife, a combined support for the surplus material and cutting bed for the knife, and means for causing the edge of the knife to 90 pass through the surplus material into contact with the bed.

2. A machine for removing surplus material projecting beyond a seam which joins 95 two or more flexible articles, having in combination, a knife, means for operating the knife, a combined support for the surplus material and cutting bed for the knife, and means for moving the support into contact with the edge of the knife to cause the 100 surplus material to be severed.

3. A machine for removing surplus material projecting beyond a seam which joins 105 two or more flexible articles, having in combination, a knife, means for moving the knife in a manner to produce a draw cut, a support for the surplus material, and means for producing relative movement of approach between the knife and the support to cause the edge of the knife to pass through 110 the surplus material into contact with the support.

4. A machine for removing surplus material projecting beyond a seam which joins 115 two or more flexible articles, having in combination, a knife, means for operating the knife to produce a draw-cut, a support for the surplus material normally spaced from the knife, said support having a narrow end adapted to be placed close to the seam, 120 and a smooth supporting face adapted to serve as a cutting block inclined to the direction of the cut to be made and located in the path of the cut, and means under the control of the operator for causing relative 125 movement between the knife and support to cause the surplus material to be severed on a bevel.

5. A machine for removing surplus material projecting beyond a seam which joins 130

- two or more flexible articles, having in combination, a band knife, means for operating the knife, a support for the surplus material, said support being normally spaced 5 from the knife, treadle controlled means for moving the support into contact with the knife to sever the surplus material, and means responsive to release of the treadle for returning the support to and holding 10 it in its normal position.
6. A machine for removing surplus material projecting beyond a seam which joins two or more flexible articles, having, in combination, a knife, means for moving said 15 knife in a manner to produce a draw cut, a support for the surplus material, said support being normally stationary and out of operative relation to the knife having a narrow end adapted to be placed close to 20 the seam and a supporting face inclined to the direction of the cut to be made, and means for causing relative movement between said knife and support to cause the surplus material to be severed on a bevel.
- 25 7. A machine for removing surplus material projecting beyond a seam which joins two or more flexible articles, having, in combination, a knife, means for operating said knife, a support located in front of said 30 knife in position to support the work with the locality to be cut below that portion of the edge of the knife to which it is to be presented, and means for raising said support and moving it into operative relation 35 to said knife.
8. A machine for removing surplus material projecting beyond a seam which joins two or more flexible articles, having, in combination, a knife, means for moving said 40 knife in a manner to produce a draw cut, a support located in front of said knife in position to support the work with the locality to be cut below that portion of the edge of the knife to which it is to be presented, and means for raising said support 45 and moving it into operative relation to said knife.
9. A machine for removing surplus material projecting beyond the seam which 50 joins the top of the upper of a shoe to the vamp, having, in combination, a support normally stationary and out of operative relation to the knife having a tapered end adapted to be inserted between the surplus 55 material and the vamp and a face which serves as a support for said surplus material, a knife, means for moving said knife in a manner to produce a draw cut, and means for producing relative movement between said knife and support to cause the 60 knife to sever said material.
10. A machine for removing surplus material projecting beyond a seam which joins two or more flexible articles, having, in combination, an endless knife, means for op- 65
- erating said knife, a support for the surplus material, said support being normally stationary and out of operative relation to the knife, and means for moving the support into operative relation to the knife to 70 cause the knife to sever said material and for returning the support to normal position.
11. A machine for removing surplus material projecting beyond a seam which joins two or more flexible articles, having, in combination, a knife, means for operating said knife continuously, a support for the surplus material, and treadle operated means for causing relative movement be- 80
12. A machine for removing surplus material projecting beyond a seam which joins two or more flexible articles, having, in combination, a knife, means for operating said knife, a support for the surplus material, said support being normally stationary and out of operative relation to the knife, and treadle operated means for moving the support into operative relation to the knife to cause the knife to sever said material. 85
13. A machine for removing surplus material projecting beyond a seam which joins two or more flexible articles, having, in combination, a knife, means for moving said knife in a manner to produce a draw cut, a support for the surplus material, said support being normally stationary and out of operative relation to the knife, and treadle operated means for causing relative movement between said support and knife to 90 cause the knife to sever said material. 95
14. A machine for removing surplus material projecting beyond the seam which joins the top of the upper of a shoe to the vamp having, in combination, a knife, means for operating said knife, a support for said surplus material, said support being normally stationary and out of operative relation to the knife, a guideway in which said support is slidable, and treadle controlled means for sliding said support toward said knife. 100
15. A machine for removing surplus material projecting beyond the seam which joins the top of the upper of a shoe to the vamp having, in combination, a knife, means for operating said knife, a support having a narrow end adapted to be inserted between said surplus material and said vamp, said support being normally stationary and out of operative relation to the knife, and means for presenting the material thus supported to the knife while maintaining said seam out of the path of the cut of the knife. 110
16. A machine for removing surplus material projecting beyond the seam which 120
- 125
- 130

joins the top of the upper of a shoe to the vamp having, in combination, a support having a tapered end adapted to be inserted between the surplus material and the vamp and a face which serves as a support for said surplus material and as a cutting bed, a cutter, and means for producing relative

movement between the cutter and the support to cause the edge of the cutter to pass through the surplus material into contact with the support.

In testimony whereof I have signed my name to this specification.

BUDD D. BOHANAN.
